(57) CLAIM

The ornamental design for a handbag, as shown and described.

DESCRIPTION

FIG. 1 is a front perspective view of a handbag showing my handbag design;

FIG. 2 is a front view of the handbag shown in FIG. 1;
FIG. 3 is a rear view of the handbag shown in FIG. 1;
FIG. 4 is a left side view of the handbag shown in FIG. 1;
FIG. 5 is a right side view of the handbag shown in FIG. 1;
FIG. 6 is a top view of the handbag shown in FIG. 1; and,
FIG. 7 is a bottom view of the handbag shown in FIG. 1.
The broken line showing of the zipper, zipper pull, and circular bag stands is for illustrative purposes only and forms no part of the claimed design.
